DESIGN FOR A SALAD SERVER

Alexander C. Weiss, Chicago, Ill.

Application November 27, 1946, Serial No. 135,134

Term of patent 7 years

(Cl. D44—4)

To all whom it may concern:

Be it known that I, Alexander C. Weiss, a citizen of the United States, residing at Chicago, in the county of Cook and State of Illinois, have invented a new, original, and ornamental Design for a Salad Server, of which the following is a specification, reference being had to the accompanying drawing, forming part thereof.

Fig. 1 is a perspective view of a salad server, showing my new design;

Fig. 2 is a side view thereof;

Fig. 3 is a plan view thereof.

I claim:

The ornamental design for a salad server, as shown.

ALEXANDER C. WEISS.
